UNITED STATES PATENT OFFICE.

RICHARD GIBBS, OF COAL VALLEY, PENNSYLVANIA, ASSIGNOR OF ONE-HALF TO SAMUEL O'NEIL, OF SAME PLACE.

POST-DRAWING DEVICE.

SPECIFICATION forming part of Letters Patent No. 290,637, dated December 18, 1883.

Application filed October 10, 1883. (No model.)

To all whom it may concern:

Be it known that I, RICHARD GIBBS, of Coal Valley, county of Allegheny, State of Pennsylvania, have invented or discovered a new and useful Improvement in Post-Drawing Devices; and I do hereby declare the following to be a full, clear, concise, and exact description thereof, reference being had to the accompanying drawings, making a part of this specification, in which—like letters indicating like parts—

Figure 1 is a perspective view of one form of my invention as shown in operation, and Figs. 2 and 3 are views of modified portions 15 of my apparatus as shown in Fig. 1.

The object of my invention is to provide an improved device for drawing or removing posts that have been used as supports for the roof of coal-mines after the coal has been taken 20 out and the necessity for supporting the roof no longer exists.

In the business of coal-mining, in the running of entries and in the digging out of the coal from the rooms, it is necessary to use a 25 great number of wooden posts to support the roof, and the number of posts needed is dependent upon the nature of the coal formation. When the roof is soft and crumbly, a greater 30 number is necessary; but in any event these posts are too valuable to be left standing in the mine after the coal is taken out, and their usefulness as supports at that particular spot is at an end; but the attempt by the miners to knock them down and take them out in the 35 usual way is attended with great danger to life and limb from the falling in of the roof as soon as the post is taken away and before they have time to get to a safe distance, and my invention is intended to obviate this danger; 40 and it consists in an apparatus composed of notched levers, tongs, and a rigid connecting-arm, the whole so arranged as to enable the miner or operator to accomplish the withdrawal of the posts with great ease and safety, 45 and while remaining at a safe distance from the point of danger.

To enable others skilled in the art to make and use my improvement, I will describe its construction and manner of use.

50 The lever-arm A is made of wrought-iron,

from four and one-half to five and one-half feet in length, and with one end shaped into a nib or hook, a, and the other end formed into a handle, a', and from near the handle portion a' to near the nib a extends a rectangular open space, a², through which may pass, at the suitably-enlarged rectangular opening a³, the rigid connecting-arm B. Notches n n n are also formed along the side of A, adapted to fit and have a bearing against the corresponding 60 notches or cogs, c, upon the connecting-arm B. The rigid connecting-arm B is also made of wrought-iron, from six to ten feet in length, as may be preferred, and may be made either with notches or cogs upon both upper and 65 lower surfaces, as shown in Fig. 1, or with the notches only upon the one surface, as shown at B in Fig. 2. At the end of the connecting-arm B, at b, I pivot the ends of a pair of arms, b', which connect, in turn, with the arms of the 70 tongs C, which are also made of wrought-iron and of strength sufficient to clasp firmly and draw out any ordinary post. At Fig. 2 is shown a modified form of B in Fig. 1, and Fig. 3 is the corresponding modified form of lever 75 or dog for it.

The operation of my invention is as follows: The notched end of the rigid connecting-arm B is passed through the rectangular opening a³ to a suitable distance, and then adjusted side-wise upon the lever or dog A, to suit the convenience of the operator. A suitable point—such as a standing post or some other solid support—is chosen as a fulcrum for the nib a of the lever or dog A, and the rigid connecting-arm B is pushed forward until the points of the tongs C come in contact with and clasp the post to be withdrawn, when it will be readily seen that by the application of the necessary pressure to the handle a' of the lever A the 80 post P will be withdrawn; and in case it should be desirable, by reason of falling coal or roof, or for any other reason, to release the hold of the tongs C upon the post P, it is easily done by pushing forward the rigid arm B, when the 85 points of the tongs will at once open. By means of the rigidity of the connecting-arm B, I am able to stand at a safe distance and manipulate the tongs C, and by means of the notches n n n and the corresponding notches, 90 95 100

ccc, all slipping of the levers upon each other is prevented, and I am able to get a firm bearing, and I can also vary the amount of power or leverage, as occasion may require, by sliding 5 the arm B nearer to or farther from the nib *a*.

My invention may be applied not only in coal-mining, but in all kinds of mining or tunneling, when it is desirable to remove a post or other object without going up close to it.

10 What I claim herein as my invention, and desire to secure by Letters Patent, is—
In a post-drawing device, the lever A, hav-

ing nib *a*, rectangular opening *a*², and enlarged rectangular opening *a*³, and notches *n n n*, in combination with rigid arm B, with its notches 15 or cogs *ccc* and tongs C, attached thereto, substantially as shown and described.

In testimony whereof I have hereunto set my hand.

RICHARD GIBBS.
